US00D599070S

(12) United States Design Patent
Hosoda et al.

(10) Patent No.: US D599,070 S
(45) Date of Patent: * Aug. 25, 2009

(54) IRON

(75) Inventors: Syuuichi Hosoda, Osaka (JP);
Fumiyasu Nakano, Osaka (JP); Kyoaki Konno, Osaka (JP)

(73) Assignee: Panasonic Corporation, Osaka (JP)

() Term: 14 Years

(21) Appl. No.: 29/335,478

(22) Filed: Apr. 16, 2009

(51) LOC (9) Cl. 07-05

(52) U.S. Cl. D32/68

(58) Field of Classification Search D32/68-72;
38/77.1-77.9, 74, 88, 90; 219/245-248

See application file for complete search history.
